UNITED STATES PATENT OFFICE.

GEORGE W. DITMORE, OF ALBANY, AND ABRAHAM B. APPLER AND CHARLES E. SCHOLL, OF WATERVLIET, NEW YORK.

MEANS FOR CONNECTING BRAKE SHOES AND HEADS.

Application filed April 2, 1920. Serial No. 370,710.

To all whom it may concern:

Be it known that we, GEORGE W. DITMORE, ABRAHAM BENJAMIN APPLER, and CHARLES E. SCHOLL, citizens of the United States, residing at Albany, Watervliet, and Watervliet, respectively, all in the county of Albany and State of New York, have invented certain new and useful Improvements in Means for Connecting Brake Shoes and Heads, of which the following is a specification, reference being had therein to the accompanying drawing.

This invention relates to means for connecting brake shoes and heads, and more particularly to a novel and improved type of retaining key, whereby to permit of the removal of the shoe from the head as desired, while retaining or locking the shoe to the head against accidental removal.

In the particular art to which the invention relates, many suggestions have heretofore been made of retaining means between the ordinary brake shoe and brake beam head, and many of these have proven to be satisfactory to a large extent, but at the same time they are all, so far as they have come to our knowledge, more or less susceptible of becoming accidentally displaced in operation, with the result that the shoe is permitted to drop off, with the result not only of the loss of the shoe, but likewise the destruction of the head, for the reason that the bearing face thereof will in the subsequent operation of the brake beam brought in forcible contact with the wheel tread, thereby wear the head and render the same unfit in a short period of time for subsequent use.

It is therefore the primary object of the present invention to overcome many of the disadvantages incident to retaining means for the shoe, as at present in use, and with this in view, it is proposed to provide a retaining key adapted to be interposed between the shoe and brake beam head, the key being of novel and improved construction and of a character adapted to be readily applied in position, and when once in position to automatically assume a retaining or locking engagement with the associated parts of the head and shoe, thus preventing accidental removal of the key, and loss of the shoe, as is frequently the case in prior

constructions wherein the usual tapered key has a tendency to drop out of place when the brake head is turned upside down during turning over of cars at loading and unloading docks, and also in other service.

It is a further object of the invention to provide a retaining key of a character applicable to the modern and improved type of brake beam head and shoe now in common usage, and without necessitating any changes whatsoever in the normal construction of these parts.

It is also contemplated by the invention to provide a locking key of the character described having in addition to the main retaining or locking characteristics thereof, means whereby should said main locking characteristics become partially displaced from the cooperating members of the shoe or head as the case may be, certain parts of the key will be brought into frictional contact with the walls of the shoe or head to resist further separation of the key from the shoe and head.

Still further, it is an object of the invention to provide a retaining key of the general type referred to, which, while strongly resisting accidental displacement from normal locking position, may upon exertion of intended pressure, be readily released, for the removal of the shoe, without breakage or destruction of parts, to the end that the key may be re-used for its intended purpose, as occasion demands.

More particularly the invention embraces a novel and improved form of retaining key, simple in design and construction, strong and durable, and efficient and satisfactory in operation.

Other improvements, and novel details in the construction and arrangement of the various parts of the invention will be appreciated from the description to follow, which, for a clear understanding of the invention, is to be considered in connection with the accompanying drawings, forming a part hereof, and wherein is disclosed for the purpose of illustration a convenient and satisfactory embodiment of the invention, though it is to be borne in mind in this connection that minor changes may be resorted to without departing from the spirit of the invention, and that the particular locking means

herein described may be susceptible of other adaptations and uses not specifically referred to herein.

In the drawings, Fig. 1 is a longitudinal vertical section of a brake shoe and brake beam head in operative connection, and retaining means, the latter shown in elevation, for the shoe and head.

Fig. 2 is a longitudinal transverse section 10 of the same.

Fig. 3 is a plan view of an improved locking key.

Fig. 4 is a side elevation of the same.

With more particular reference to the 15 drawings, wherein like reference numerals refer to corresponding parts throughout the several views, 1 designates generally a brake shoe of standard construction having the usual wheel-engaging surface 2, and curved 20 rear head-engaging surface 3, with the central lug 4 having a longitudinally-extending opening 5 therethrough.

6 designates generally a brake beam head of any of the approved types having projecting from the inner surface 7 thereof a 25 pair of lugs 8 and 9, respectively, one adjacent each end of the lug 5 of the brake shoe, and having inclined surfaces 10 corresponding with the general inclination of the inclined surfaces 11 of the said brake shoe lug 5. The lugs 8 and 9 of the brake beam head have longitudinally-extending openings 8^a and 9^a extending therethrough.

Referring now more particularly to the 35 novel and improved means for retaining the brake head and shoe in the interlocked condition illustrated, 12 is an offset or upstanding head which connects with a body portion 13 thereof the lock being curved preferably throughout its length, to correspond with the general curvature of the shoe and head, and in thickness, said body part tapering gradually to a reduced thickness at the lower end thereof, as illustrated more 45 particularly in Fig. 4.

At said lower end of the locking pin, the same is provided with a central terminal slot 14, thereby providing furcations 15 which are bent and separated in any desired manner at a point adjacent to but spaced below the upper end of the slot whereby to provide the abrupt shoulder parts 16, which shoulder parts connect with oppositely inclined edges of the arms 15, which said edges 55 gradually converge towards the lower end of the key as illustrated at 17.

It will be observed that the arms 15 as thus constructed will constitute spring arms requiring considerable compression to draw 60 the arms adjacent to or in contact with one another, so as to constitute in effect continuations of the side edges 18 of the body part of the key.

The key as above described may, and 65 preferably does, have an auxiliary retain-

ing characteristic, conveniently formed by slitting or shearing a section 19 from each side thereof extending from a point adjacent the head 12 to a point considerably therebelow.

In the application of the key to the brake shoe and head, assuming that the key is used for this purpose (of course this is its intended primary use), the lugs or arms 17 at the shouldered portions 16 thereof are 70 expanded to a width somewhat wider than the width of the opening 9^a, whereby when in place the shouldered portions 16 will project outwardly beyond the side walls of the lug 9 surrounding said opening, as illustrated more particularly in Fig. 2.

What we claim as new and desire to secure by Letters Patent of the United States, is:

1. A means for locking brake shoes to 85 heads, the shoe and head having registering apertured lugs, the said means comprising an elongated key split at its inner or lower end to form side arms, which said arms are spread whereby to provide lateral 90 enlargements at a point spaced from said end, and said side arms gradually converging towards said lower end from said enlargements, whereby to facilitate insertion of the key through the apertures of the lugs, 95 and whereby said enlargements upon the insertion of the key will spring outwardly to a point beyond the wall of the recess of the adjacent lug, and said key also having adjacent its upper or outer end split parts 100 forming spring side retaining enlargements.

2. A locking means for brake shoes, comprising an elongated key curved substantially throughout its length whereby to conform to the general curvature of the shoe, 105 said key having a head at one end and being gradually reduced in thickness toward its opposite end, the said key having at said opposite end integral lateral substantially bow spring locking arms, and also having 110 adjacent said head auxiliary spring locking means.

3. A locking key for connecting brake shoes to heads, said key being curved throughout its length and having a head at 115 one end, and being split at its opposite end to form opposed side arms offset intermediate the ends thereof to form spring locking projections, and said key having adjacent the head split side parts laterally offset to form substantially bow-shaped 120 spring locking means.

4. A key for locking brake shoes to heads, comprising an elongated member tapering in thickness substantially throughout the length from the head thereof so as to 125 form a relatively thin engaging end, and a plurality of longitudinally spaced lateral projections forming locking springs.

5. A key for connecting brake shoes to 130

- heads, comprising an elongated member gradually reduced in thickness from the head to the insertible end thereof, and a plurality of longitudinally spaced integral laterally projecting bow spring members adapted to engage at opposite sides of the usual interengaging lugs on the shoe and head, and adapted to be compressed on the insertion and removal of the key.
10. 6. A locking key for securing brake shoes to heads, which comprises an elongated body part provided with head and end portions, the end portion having spaced members, and a laterally offset portion partially severed from the main part to form yieldable retaining means located between the head portion and the inner terminal of the spacing at the end portion.
7. A locking key for securing brake shoes to heads, which comprises an elongated curved body part gradually reduced in thickness from its head to the insertible end thereof, the upper and lower surfaces of the body part being substantially smooth and continuous, the said body part being split therethrough longitudinally from its insertable end outwardly a considerable distance whereby to form side arms, which side arms are normally offset laterally to form retaining projections, but which are adapted to yield under pressure towards, or in contact with, one another, and auxiliary compressible lateral spring arms on the body part adjacent the head of the key.
8. In combination with a brake shoe and head having overlapping apertured lugs, a locking key adapted to be inserted through said lugs having lateral spring means to engage the sides of the adjacent parts of the shoe and head at opposite ends of said lugs.
9. In combination with a brake shoe and head having overlapping apertured lugs, a locking key adapted to be inserted through said lugs, said key having integral spring arms to engage one above and one below said lugs, substantially as and for the purpose described.
10. In combination with a brake shoe and head having overlapping apertured lugs, a locking key adapted to be inserted through said lugs, the said key having at the lower end thereof integral bow spring arms adapted to yield to permit of the insertion of the key and to thereafter spring beyond the wall of the lugs surrounding said apertures.
11. In combination with a brake shoe and head, one of which has a plurality of lugs and the other an intermediate interengaging lug, the said lugs having registering apertures therethrough, and a locking key to be inserted through said apertures, comprising an elongated body part curved and tapered in thickness throughout its length, the said body part at its insertible end being split and spread to form locking arms, adapted to be compressed on the insertion and removal of the key through said apertures, and when in normal position to project beyond the wall of said apertures, and said body part also having adjacent its opposite end integral lateral bow spring arms to engage over the walls surrounding the apertures of the lug adjacent the head end of the key.
12. A locking means for brake shoes comprising an elongated key having a head on one end and the opposite end slit longitudinally to form arms, said arms being bent laterally to extend beyond the sides of the key body, and spring arms formed adjacent the head end, said spring arms being formed by longitudinally slitting the key adjacent the longitudinal edges and then bending to form a curved extension beyond the edge of the key, one end of the arms being severed from the body of the key but in sliding engagement therewith.
13. A locking means for brake shoes comprising a key having spring arms intermediate its ends, said arms being formed by longitudinally slitting the key adjacent its longitudinal edges and then bending to form a curved extension beyond the edge of the key, one end of the arms being severed from the body of the key but in sliding engagement therewith.
14. A device for connecting brake shoes to heads comprising an elongated key split at its inner or lower end to form side arms, which said arms are spread whereby to provide lateral enlargements at a point spaced from said end, and said side arms extending a substantial distance beyond the enlargements and converging in straight easy lines from said enlargements to their lower ends to provide an elongated introducing portion in advance of the enlargements.
- In testimony whereof we hereunto affix our signatures in the presence of two witnesses.
